UNITED STATES PATENT OFFICE

169,272

VAPORIZER

Jay Morey, Madison, Wis., assignor to Universal Electric Products Corp., Madison, Wis., a corporation of Wisconsin

Application July 5, 1952, Serial No. 20,471

Term of patent 3½ years

(Cl. D31—3)

To all whom it may concern:

Be it known that I, Jay Morey, a citizen of the United States, residing at Madison, in the county of Dane and State of Wisconsin, have invented a new, original, and ornamental Design for a Vaporizer, of which the following is a specification, reference being had to the accompanying drawings, forming part thereof.

Fig. 1 is a plan view of a vaporizer showing my new design;

Fig. 2 is a bottom plan view thereof;

Fig. 3 is a rear elevational view thereof;

Fig. 4 is a side elevational view thereof; and

Fig. 5 is a front elevational view thereof, drawn to an enlarged scale.

I claim:

The ornamental design for a vaporizer, substantially as shown.

JAY MOREY.
